J. H. HORNER
MACHINE FOR PRINTING WORDS AND FIGURES ON CHECKS,
DIVIDEND WARRANTS, AND THE LIKE
Filed Feb. 3, 1925

FIG. 3

FIG. 4
Inventor
J. H. Horner
by *Perkins* 11/24.

UNITED STATES PATENT OFFICE.

JAMES H. HORNER, OF LONDON, ENGLAND.

MACHINE FOR PRINTING WORDS AND FIGURES ON CHECKS, DIVIDEND WARRANTS, AND THE LIKE.

Application filed February 3, 1925. Serial No. 6,566.

To all whom it may concern:

Be it known that I, JAMES HOWARD HORNER, a British subject, residing at 10 Castleton Road, Upper Walthamstow, London, E. 17, England, have invented certain new and useful Improvements in or Relating to Machines for Printing Words and Figures on Checks, Dividend Warrants, and the like, of which the following is a specification.

This invention relates to machines for printing both words and figures and such as are employed for writing checks, dividend warrants and the like.

15 In a general way the machines are set by keys or, as described in the specification of my application for Letters Patent Serial No. 663,480, by levers and the words and figures are arranged on two parallel rollers 20 made from a number of independently rotatable sections which are turned by the keys or levers to present the correct words and figures to the platen upon which the check, dividend warrant or the equivalent is placed.

25 In a general way these two printing rollers are spaced apart a definite distance and it follows, therefore, that if the words and figures are to be printed simultaneously the check or other form on which they are 30 printed must have its lines or spaces for the words and figures appropriately spaced so that the printing is effected in the correct positions. This may mean the printing of special forms to suit the machine and 35 the one machine cannot be easily and quickly used for other forms which have the said spaces further apart or closer together.

According to the present invention I provide means whereby the platen or roller carrying the paper to be printed can be shifted both vertically and horizontally so that the printing of the words in one space can be effected and afterwards the printing of the figures in another space is done. The movements of the platen, which is preferably a 45 roller, can be limited by set screws or other known or convenient devices which when set enable the operator to quickly and accurately shift the said roller from one position to another. Instead of first printing the words, the figures may be printed and the words may be impressed as the second print.

55 I may also provide, as hereinafter described, means for printing the figures twice

so that the same can be printed on the counterfoil or stub of the check or other such form.

The movements of the platen or roller can be effected in various ways and I will 60 describe one method with reference to the accompanying drawings in which:

Fig. 1 is a top view of a roller 1 movably fitted to a hinged back 2 which may be part of a machine of any suitable kind say 65 of the type first herein referred to and in which two separate rollers one bearing figures and the other letters are employed for printing on checks and other forms.

Fig. 2 is a front view of the same roller 70 and hinged back as seen from the front of the machine although the body or frame of the machine would be right in front of the said roller and hinged back.

Fig. 3 shows the same parts from an end 75 view, that is as seen from the side of the machine, part of which is indicated at *a* and has the frame pivoted to it at *z*.

Fig. 4 shows a detail connected with the printing rollers and whilst no part of my 80 invention is included for the purpose of making the operations clear.

In this example the roller 1 has a paper guard or holder 3 and is furnished with set screws 4, 4 to limit its endwise movements. The roller is carried in a frame 5 which has a dovetailed rib 6 which fits into a groove in a carrier 7 provided with vertical dovetail grooves 8 fitting over ribs 9 on the frame 2. The rib 6 permits of the horizontal movements of the roller and the ribs 9 permit the vertical or rising and falling movements of the roller. The two vertical positions of the roller are shown in Figs. 2 and 3 by full line and line and dot. Any 95 suitable means for holding the roller in either position may be employed and I show two spring controlled catches 10 adapted to be withdrawn by a lever 11 to permit the roller to drop from the higher to the lower position, said catches having sloped under faces so that they will be automatically depressed when the roller is raised by hand and will re-engage the underside of the carrier when it is lifted above them.

100 It will be understood that after the printing rollers indicated at *b* and *c* are set and the paper to be printed upon has been placed on the roller 1, the frame 2 will be brought forward by the links and lever *d*, *e* and *f* 110

and will press the paper against the roller *b* and thus print the amount in words on the appropriate part of the paper, after which the lever 11 is moved to withdraw the 5 catches 10 and the roller 1 will drop to the lower position for the printing of the amount in figures the roller having been appropriately turned to bring the space for the figures into position. The positions for the 10 printing are readily seen a short distance above the paper guard 3 in much the same manner as is common on typewriters. India rubber buffers are provided at 14, 14.

In Fig. 4 I show some of the sections of 15 the figure rollers at *c* and have marked the figures 1214—10—6 on same as an imaginary amount for the purpose of showing how the roller 1 can be lengthwise set to accept the printing in the proper place. Under the 20 roller and mounted on the carrier 7 is a plunger 12 controlled by a light spring and adapted to take into notches 13 in the carrier 5. These notches are sufficient to retain the roller in place but the spring can be easily 25 overcome by intentional endwise movement of the roller. When four figures in the pounds column, say the 1214 above mentioned, are to be printed, the plunger will be in the end notch as shown. If three figures 30 only are to be printed the platen will be moved one notch to the right, and so on, the particular advantage of same being that the figures can be set close to the £ printed on the check or other form for them and the 35 roller will be held in place when set.

For the purpose of printing on the stub or counterfoil the roller is moved lengthwise until the stub comes into position and the printing of the figures is then effected.

40 It must be understood that any other suitable platen and not necessarily a roller may be employed and there are various ways in which it can be raised and lowered or moved lengthwise.

45 What I claim is:—

1. A hand operated printing machine having a pivoted frame and a platen which is vertically movable on the frame.
2. A hand operated printing machine having a pivoted frame and a platen which is horizontally movable on the frame.
3. A hand operated printing machine having a pivoted frame and a platen which is movable both vertically and horizontally on the frame.
4. A hand operated printing machine having a pivoted frame and a platen which is vertically and rotatably movable on the frame.
5. A hand operated printing machine having a pivoted frame and a platen which is

horizontally and rotatably movable on the frame.

6. A hand operated printing machine having a pivoted frame and a platen which is 65 movable vertically, horizontally and rotatably on the frame.

7. In a machine for printing variable amounts, say money values, in both words and figures and in which the type for same 70 is arranged on two rollers, a platen of roller form, adapted to hold the paper on which the words and figures are to be printed, and means whereby the platen may be caused to rise and fall and to be brought to the respective rollers 75 successively.

8. In a machine for printing variable amounts, say money values, in both words and figures and in which the type for same is arranged on two rollers, a platen adapted 80 to hold the paper on which the words and figures are to be printed, and means whereby the platen may be caused to rise and fall and to be brought to the respective rollers successively.

85 9. A printing machine having two parallel rollers each comprising a plurality of sections, the sections on one roller carrying letters and the sections on the other roller carrying figures, hand operated means for variably rotating the sections, a movable frame adjacent the rollers, a platen on the said frame, means for moving the platen vertically and means for moving the frame so as to bring a paper on the platen against 95 one of the rollers, means for shifting the platen on the frame so that a second like movement of the frame will bring the paper on the platen against the other roller.

10. A machine for printing values in 100 words and in figures in which the words and the figures are set by hand-operated means, such as levers or keys, adapted to actuate a plurality of sections in two rows, one row carrying letters and the other row carrying 105 figures, said sections being mounted on parallel axes, a movable frame adjacent the sections, a platen mounted on the frame and means whereby the platen can be moved on the frame and held in any required position 110 thereon and so that when the frame is moved a paper on the platen can be brought first against either of the rows of sections and after the platen is shifted, can by again moving the frame be brought against the 115 other row of sections so that the required value can be printed first by one of the rows of sections and then by the other row of sections.

In testimony whereof I affix my signature

JAMES H. HORNER.
